UNITED STATES PATENT OFFICE.

GEORGE WESTON CRAIG, OF PROVO CITY, UTAH.

RAILROAD-TICKET.

SPECIFICATION forming part of Letters Patent No. 669,076, dated March 5, 1901.

Application filed May 9, 1900. Serial No. 16,042. (No model.)

To all whom it may concern:

Be it known that I, GEORGE WESTON CRAIG, a citizen of the United States, and a resident of Provo City, in the county of Utah and State of Utah, have invented new and useful Improvements in Railroad-Tickets, of which the following is a full, clear, and exact description.

My invention relates to railroad-tickets of the class known as "coupon-tickets," and has for its object to provide features of improvement and increased usefulness in a ticket of the kind described and shown in my application for Letters Patent, Serial No. 734,792, filed October 26, 1899. As in said former construction, the object of the invention is to provide a ticket-form which will be available, by appropriate punch-marks, for travel between various points and which will particularly enable the ticket-agent to give the passenger (with only one form of ticket) a choice of any of the routes available for the particular journey intended.

The present improvement has for its object mainly to facilitate the selection and designation of the railroad-lines available by grouping the names of such lines in the order in which they are used, as will be fully described hereinafter, and particularly pointed out in the claims.

Reference is to be had to the accompanying drawings, forming a part of this specification, in which similar characters of reference indicate corresponding parts in all the figures.

Figure 1^a is a plan of the left-hand portion of a ticket embodying my invention. Fig. 1^b is the right-hand continuation of Fig. 1^a, and Fig. 2 is a broken sectional view of the folded ticket.

The ticket shown in the drawings is a three-coupon ticket—that is, one coupon will be good for passage from the starting-station to a junction-point, the second coupon from this junction-point to another junction-point, and the third to the final destination. The principles of construction described hereinafter may, however, be applied to any ticket having two or more coupons or sections.

The ticket shown comprises the following parts: a "general-information" section A, three passenger-coupons B C D, and an agent's stub E. The ticket is adapted to be folded

along the lines *a a*, which separate the sections from each other, and, if desired, folding may be facilitated by scoring or perforating the ticket along said lines. Such means would also facilitate the successive tearing off of the ticket-sections.

The general-information section A (see Fig. 1^a) has a blank space for the insertion of any remarks or matter the company may desire to add, such as a description of the purchaser or his signature or other means of identification. At the margin of this section appear the usual indications of the time-limit by year, (in space A¹), month, (in space A²), and day, (in space A³). At the bottom is an "Index to junction-points" A⁴, having blank spaces, as at A⁵, to be filled in by writing or in any other manner by the agent issuing the ticket. When these blanks have been filled, as shown, the index will designate not only the terminal-stations of each coupon, but the line available for each of the coupons. Thus in the example shown the ticket is issued for passage "From Provo City to Chicago," the first coupon entitling the holder to passage "From Provo City to Ogden via the New York and San Francisco line," the second coupon reads "From Ogden to Council Bluffs via the Union Pacific," and the third entitles the passenger to transportation on the Chicago and Northwestern from Council Bluffs to Chicago. As all this appears on the index A⁴, which remains connected with the ticket until the end of the journey, the perpetration of fraud by changing the coupons is practically made impossible.

The passenger-coupons B C D and the agent's stub E are practically alike, differing from each other by details in the heading in the space at the top. Thus coupon B is "Good only from junction-point via line number three and to final destination," while the wording is appropriately changed for the other coupons and for the agent's stub. Another difference between these coupons and the stub will be pointed out hereinafter; but I shall first describe those features in which they are alike. Each of the said parts has a list of lines which may be available with blank spaces F' to receive indications in writing, or preferably by punches, as to the particular lines selected by the passenger and

the order in which they are to be used. The list of lines is divided into as many groups as there are coupons—that is, three in the case shown—and in the first group F appears 5 the line (or lines) on which the journey is or may be started. In the second group F² is a list of lines No. 2—that is, of lines on which the passenger may continue his journey after leaving the line on which he began 10 his journey, and the third group F³ contains a list of the lines which the passenger may use to the final destination. Further, in a section G, under the heading "Class," are proper indications and blank spaces to specify 15 the conditions to which the ticket is subject, also, if desired, a blank space for the reception of a baggage-punch mark. At the bottom (or at any other convenient place) is a series of spaces H for the punch-marks of the 20 several conductors. The body of each coupon and of the stub comprises four sections or lists, (or, generically speaking, one in excess of the number of passage-coupons the ticket contains,) of which the first, I, contains a list 25 of starting-stations and first junction-points, preferably with one or more blanks, so that the name of a less important station may be written in such blank space. The second section I' contains a list of the various junction-stations at which a traveler coming from 30 one of the starting-stations (in list I) may pass upon a connecting-line, together with further junction-points of such connecting-lines. The third section I² contains a list of 35 the several junction-stations at which a passenger, having traveled over the first-mentioned connecting-line, may be transferred to another connecting-line to reach his final destination, which may be any one of the stations 40 indicated in the list appearing in the section I³. Adjacent to each station-name in the various lists is a space, preferably numbered, as shown, to receive a punch-mark.

While the matter contained in the spaces 45 F F² F³ G I I' I² I³ is the same for each of the coupons B C D and for the stub E, its arrangement is different in the coupon C and stub E (which are alike in this particular) from the coupons B and D, which again are alike, 50 except as to the heading. Sections B and D have the arrangement of sections C and E reversed from left to right, and vice versa—that is, the central columns of station-names are the same, but what is the right-hand column in the sections B and D becomes the left-hand column in the sections C and E, and vice versa. Similarly, the spaces F F² F³ G are at 55 the left in sections B and D and at the right in sections C and E, also in sections B and D 60 the numerals are at the left of station-names, and in sections C and E they are at the right of such names. The purpose of this arrangement is to bring those spaces of the several sections which are adapted to receive corresponding punch-marks into exact superposition 65 when the ticket is folded as shown in

Fig. 2, so that all of the four parts B, C, D, and E may receive their corresponding punch-marks J at the same time.

The improved ticket is used as follows: 70 Let us assume the passenger desires a ticket from Provo City to Chicago via the New York and San Francisco line to Ogden, the Union Pacific to Council Bluffs, and the Chicago and Northwestern. The ticket-agent punches the 75 date at A' A² A³ in the usual manner and inserts in the spaces A⁵ of the index A⁴ the indications shown in Fig. 1^a. The agent then folds the ticket along the lines a a, as indicated in Fig. 2, and then punches the four 80 sections B C D E, as indicated in Figs. 1^a and 1^b—that is, in the list F, headed "Line No. 1," the space F' opposite "N. Y. & S. F." (New York and San Francisco;) in the list F² of "Lines No. 2," the space F' opposite "Un. 85 Pac." in the list F³ of "Lines No. 3," the space opposite "C. & N. W." In the station-list I the station "Provo City" is punched. The station "Ogden" is punched both in the list I and in the list I'. The station-name "Council 90 Bluffs" is punched in the lists I' and I², and the final destination, "Chicago," is punched in the last list I³. The nature of the ticket—for instance, "First class limited"—is also indicated by a punch-mark in one of the spaces 95 of the section G, if necessary. The agent then tears off his stub E, which he keeps, as usual. The baggage-master will then punch the ticket, if required, and the section A may be folded over the others, so that the ticket 100 will be more handy to carry. The conductors will put their respective punch-marks in the spaces H, and the coupons D, C, and B will be retained by the last conductor of each line, as customary.

It will be seen that the improved ticket will 105 avoid the necessity for a multiplicity of forms and will enable any agent to issue tickets good over a large variety of routes, while the manipulations in punching the ticket are so 110 obvious that mistakes on the part of the issuing-agent are not likely to occur. As each of the sections by its punch-marks (or as for the section A by the index A⁴) gives full details as to the stations between which the 115 ticket is good and what lines should be traveled over, the use of the ticket upon other lines connecting the same stations is made impossible and fraudulent alterations of the ticket are effectively prevented. By having 120 the lines grouped in the lists F F² F³ in the same order in which they are used in traveling the succession in which the lines are to be traveled over will be obvious without the use of numerical punches and a further 125 security against fraud is obtained.

It will be obvious that the ticket might be 130 somewhat simplified by the omission of the lateral columns in the lists I and I', in which case the name of each junction-point would have to be punched only once. The addition of the lateral columns, however, is of moment

for the auditor's convenience, and I therefore consider said lateral columns not only a useful feature of my ticket, but necessary thereto.

It is to be understood that I do not limit myself to the exact arrangement of my improved ticket as shown and described, as such arrangement may be varied without departing from the spirit of my invention, and I consider myself entitled to all such variations as come within the scope of my claims.

Having thus described my invention, I claim as new and desire to secure by Letters Patent—

1. A coupon-ticket comprising a plurality of sections each having a list of starting-lines arranged in a group by themselves and a separate list of lines available for the completion of the journey, so that by appropriate punch-marks for one line of each list, the names of the lines over which the ticket is to be available, and their succession can be indicated.

2. A coupon-ticket comprising a plurality of sections having a list of lines arranged in successive groups each provided with a heading, the headings containing consecutive numbers, as "Line No. 1," "Line No. 2," &c., the starting-lines only appearing under the heading "Line No. 1," and the second or connecting-lines only under the heading "Line No. 2" so that by appropriate punch-marks for one of the lines of each group, the ticket will indicate the lines over which it is available, and at the same time the order in which the said lines are to be used.

3. A coupon-ticket, comprising a plurality of sections each having a list of stations ar-

ranged in successive groups, and a separate list of lines likewise arranged in successive groups that is, one group containing lines available for the start, and other groups containing lines available for the completion of the journey, so that by appropriate marks in both lists, the ticket can be made to read for a journey between any two points named in the station-list, over any one of the lines available between said points, and to indicate at the same time the order in which the lines are to be used.

4. A coupon-ticket, comprising a plurality of sections each having a list of lines arranged in groups having appropriate indicating means, one group containing lines available as starting-lines, and the others lines available for the continuation of the journey, the groups following each other in the same order in which the lines are to be used, and a list of stations entirely independent from the list of lines, so that the elements of the two lists may be combined with each other in various manners by appropriate marks, the station-list being likewise in a plurality of groups having appropriate indicating means one of which groups contains starting-points, another junction-points, and yet another destination-points.

In testimony whereof I have signed my name to this specification in the presence of two subscribing witnesses.

GEORGE WESTON CRAIG.
